UNITED STATES PATENT OFFICE.

FRANK LESLIE HARMON, OF BEVERLY, MASSACHUSETTS, ASSIGNOR, BY MESNE
ASSIGNMENTS, TO UNITED SHOE MACHINERY CORPORATION, OF PATERSON,
NEW JERSEY, A CORPORATION OF NEW JERSEY.

BUTTON-ATTACHING AND FASTENER-SETTING MACHINE.

1,282,225.

Specification of Letters Patent. Patented Oct. 22, 1918.

Application filed March 4, 1915. Serial No. 12,142.

To all whom it may concern:

Be it known that I, FRANK L. HARMON, a citizen of the United States, residing at Beverly, in the county of Essex and State 5 of Massachusetts, have invented certain Improvements in or Relating to Button-Attaching and Fastener-Setting Machines, of which the following description, in connection with the accompanying drawings, is a 10 specification, like reference characters on the drawings indicating like parts in the several figures.

This invention, in its more particular aspect, relates to machines for attaching buttons to stock material such, for example, as the button flies of boots and shoes, and particularly to machines for attaching the buttons by means of metallic fasteners such as staples or the like. It will be apparent, 20 however, from a consideration of the construction and mode of operation of the illustrative machine that, as far as many of the various features of the invention are concerned, it is immaterial what may be the 25 form or ultimate use or purpose of the fasteners or the buttons, or the character of the work which is operated upon.

An important object of the invention is to provide in a machine for attaching buttons by staples an organization by which the button may be presented with its eye substantially parallel with the work and the staple may be driven with one leg inside the button eye and the other leg outside of it. 30 To this end an important feature of the invention consists in means for presenting in attaching position a button with its eye substantially parallel with the work, and means for driving a staple with one leg of the 35 staple relatively close to the portion of the button eye which is outside of the staple. In this organization the driver is constructed and arranged to enter the button eye with its outer edge close to the portion of the button 40 eye which is outside the staple. This driver constitutes another feature of the invention and as herein shown is formed with a projection which enters the button eye and is of sufficient width to force a portion of the 45 head of the staple into close engagement with the work while leaving enough space between it and the portion of the button eye

which is within the staple to receive the part of the staple head which is between that portion of the button eye and the driver projection. An important advantage of this organization is that it obviates the danger of clamping the button eye close to one of the legs of the staple and between the head of the staple and the stock, a difficulty which 55 has heretofore been experienced in machines of this type. A further advantage is that a driver constructed and operating as above indicated may be utilized in feeding the stock while its projection which enters the 60 button eye is in engagement with the driven staple. The driver is preferably formed to engage substantially the entire head portion of the staple and is shown as shaped to correspond with the shape of the novel staple 65 illustrated in the drawings which forms the subject-matter of another application, Serial No. 834,914, filed April 28, 1914.

Further features of the invention are to be recognized in novel and improved mechanism through the operation of which, in the illustrated embodiment, a fastener is taken by a driving member from the end of a raceway or like supplying means and by one continuous movement is advanced 70 through the eye of a button at the end of a button raceway and into the work. In the construction herein shown this mechanism comprises a pivoted lever and a fastener inserting or driving member carried by the 75 lever and coöperating with a suitable anvil to set the fastener in the work.

Other features are to be recognized, broadly, in novel and improved mechanism for feeding the work, comprising, in the 80 preferred embodiment, means for effecting an additional feeding movement, preferably in a straight path, of the fastener securing or inserting means. In the illustrated machine both the driving member and the co-operating anvil are movable to feed the work subsequent to the driving movement of said member. To this end, the anvil is mounted upon a movable slide to which is pivoted the 85 lever which carries the driving member, and the lever is operated to insert the fastener and clench it upon the anvil, after which the slide is moved to carry both the driving member and the anvil a sufficient distance to 90

bring the work into position to receive the next operation. The driving member and the anvil are then separated and returned to their first positions.

5 The invention includes also, as features of the work feeding mechanism, novel means for relieving the pressure upon the work of the fastener inserting and securing instrumentalities during the feeding movement, so as to avoid undue wear of the mechanism, and novel means whereby adjustment may be effected to secure variations in the extent of the feeding movement of the work.

10 15 A further feature of the invention consists in means for controlling the position of the work between and preferably during the feeding movements. The preferred construction shown comprises mechanism for subjecting the work to a continuous yielding pressure, and includes a yielding presser member for engaging the work upon the same side of the anvil and a coöperating work positioning member for engaging the opposite side of the work, the yielding member being movable to permit the work to be inserted in the machine and adjusted in the desired position upon the anvil.

Further features of the invention reside 30 in a novel construction and arrangement for effecting said coöperative relation between the driving member and the means for presenting the fasteners and the buttons as to permit a fastener to be driven and a button 35 to be attached to the work under an impulse of the driving member and to facilitate the presentation of the buttons and the fasteners in succession in coördination with the movements of the driving member.

40 45 The above and other features of the invention, including certain details of construction and combinations of parts, will now be described with reference to the accompanying drawings and pointed out in the claims.

In the drawings,

Figure 1 is a view in side elevation, with portions shown in section, of a machine which constitutes the preferred embodiment 50 of the invention.

Fig. 2 is a similar view of the opposite side of the machine,

Fig. 3 is a vertical section on the line 3—3 of Fig. 1,

55 Fig. 4 is a fragmentary view showing in perspective, with the outer casings removed, the staple and button conveying mechanisms and portions of the raceways,

Fig. 5 is a view in transverse section of 60 the button raceway,

Fig. 6 is a detail view of a portion of the mechanism for adjusting the length of the feed movements,

Fig. 7 shows the delivery end portions of 65 the raceways and illustrates the manner of

presenting a button in position for attachment to the work,

Fig. 8 is a view from a different angle of the mechanism shown in Fig. 7, and shows a staple as advanced through the eye 70 of the button,

Fig. 9 is a detail sectional view showing the relation of the button to the path of movement of the driver, and

Fig. 10 illustrates the manner of setting 75 the staples in the work.

The machine receives its operative movements from a pulley 2, which is to be driven by a suitable belt, not shown, and is mounted loosely upon a shaft 4 supported for rotation in bearings formed in upright extensions of the base 6. The pulley is to be operatively connected with the shaft by any suitable form of clutch, preferably a Horton clutch, which includes a dog 8 normally 85 in contact with a cushion spring 10 on the end of a clutch actuating lever 12 in position to release the clutch and permit the pulley to rotate idly on the shaft. The lever 12 has a connection 14 leading to a suitable treadle, and is held normally by a spring 16 in the position shown in Fig. 1. With this arrangement, movement imparted to the lever 12 from its treadle serves to release the dog 8 and effect the setting of the 95 clutch, thereby causing the machine to operate during each complete revolution of the shaft 4 to attach a button to the work and advance the work into position for the next button attaching operation, as will be subsequently explained. As long as the treadle is depressed the machine will continue to operate, attaching the buttons in succession at equally spaced intervals, and when the treadle is released the button attaching instrumentalities will come to rest in the positions in which they are shown in Figs. 1 and 2.

Connected with the pulley 2 by a belt 18 is a pulley 20 keyed to a shaft 22 from which 110 rotation is imparted to the conveyers for transferring the buttons and the staples from their hoppers to the respective raceways. Secured to the opposite end of the shaft 22 is a crank disk 24 provided with an adjustable crank pin 26 from which is operated a pitman 28 connected pivotally to a block 30 which has a circular bearing portion mounted rotatably upon a sleeve member 32 keyed in turn to a second sleeve member 34 which has a bearing in the side of the staple receptacle or hopper 36 and carries at one end the staple conveyer 38. The block 30 carries a spring held pawl 40 which coöperates with ratchet teeth 42 upon the member 32, as shown in Fig. 3, so as to impart to the conveyer 38 a limited forward movement of rotation at each forward throw of the pitman 28. Within the sleeve 34 is a shaft 44 which has a squared end 130

portion fitting in a complementary recess in the side of the rotatable button conveyer 46. The shaft 44 is rotatable independently of the sleeve 32, and the means for operating this shaft includes a pawl and ratchet mechanism comprising a ratchet wheel 48 keyed to the shaft and a spring held pawl 50 carried by a block 52 similar to the block 30 and having pivotally connected thereto a link 54 which is slotted to provide a slide-way for a block 56 pivotally mounted upon a block 58 secured to the pitman 28. With this arrangement each forward throw of the pitman will serve to impart movement first to the staple conveyer 38, and subsequently, when the block 56 arrives at the end of the slideway in the link 54, to both the conveyers 38 and 46 together, bringing them simultaneously into position to deliver their articles to the respective raceways. The lost motion connection between the pitman 28 and the link 54 is provided for the reason that the number of staple carrying arms on the conveyer 38 is less than that of the button receiving recesses in the conveyer 46, as shown in Fig. 4, and for the same reason the number of ratchet teeth 42 is proportionately less than the number of teeth on the wheel 48. Similarly, reverse movement of the pitman 28 serves to retract first the block 30 and then simultaneously therewith the block 52, so as to bring the respective pawls into position to engage the teeth next in order in the series. In order to prevent overrunning of the two conveyers, the sleeve 32 is formed with a friction wheel 60, and the shaft 44 is provided with a similar wheel 62, these wheels turning in frictional contact respectively with spring pressed friction blocks 64 and 66; and in order to prevent overthrow of the pawl carrying block 52, the circular bearing portion thereof is in frictional engagement with a spring pressed friction member 68.

The buttons are held in a receptacle or hopper 70, the bottom of which is connected with an auxiliary receptacle 72 formed at one side with a circular opening in which is mounted the button conveyer wheel 46. The outer end face of this wheel is flat and provides a circular projecting flange 74 which serves to close substantially the opening in the receptacle, and the inner end portion is of reduced diameter and formed with a conical peripheral surface converging toward the receptacle and providing seats for the button heads, the wheel having slots 76 for the reception of the button eyes. The walls of the receptacle about the periphery of the button wheel present an inclosing surface inclined in substantially parallel relation to the conical surface of the wheel, and the bottom of the receptacle slopes toward the wheel so as to direct the buttons thereto. In operation, the buttons will find

their way into the space between the reduced portion of the wheel and the surrounding wall with their eyes in the slots 76, the wall serving to confine the heads closely and thereby retain the buttons with their eyes in the slots. In order to prevent the buttons from slipping off the conveyer as they are advanced toward the upper portion of their path of movement, a guard 78 is located in position to serve as a retainer for the button heads.

From the above description it will be evident that if it is desired to use buttons provided with heads that are larger than usual, the conveyer 46 should be adjusted farther toward the left than shown in Fig. 3, so as to provide a larger space for the reception of the heads between the periphery of the wheel and the surrounding wall. Such adjustment is provided for through the mounting of the conveyer 46 for rotation upon a reduced portion of a spindle 80 which is supported for endwise adjustment in a bearing in the side of the receptacle 72 and has a head 82 by means of which such adjustment may be readily effected. A set screw 84 serves to retain the spindle in adjusted position. The shaft 44 is pressed endwise toward the wheel 46 by a spring 86, and has secured upon its other end a head 88 which serves to limit such endwise movement of the shaft and provides also means by which the shaft may be manipulated to adjust its squared end in proper relation to the recess in the wheel 46. When the set screw 84 is loosened the spring 86 will thus automatically adjust the parts in the positions represented in Fig. 3. If it is desired, however, to provide more clearance for the buttons about the carrier wheel, the spindle 80 and the shaft 44 should be pressed toward the left by means of the head 82, and the set screw 84 then tightened. This arrangement provides also convenient means for releasing the buttons if they should become jammed between the carrier and the surrounding wall, as well as for emptying the receptacle 72, and to receive the buttons thus released the machine is provided with a chute 90.

The staples, as will be clearly apparent from a consideration of Fig. 4, are picked up by the forwardly projecting pointed ends of the arms of the conveyer 38, and slide inwardly along the forward edge of each arm and then outwardly along the rear edge of the preceding arm from which they are delivered to the staple raceway. Although the ends of the arms move in close proximity to the walls of the receptacle 36 so as to prevent the staples from passing between the walls and the arm end, any tendency for displacement of the staples through frictional contact with the walls is avoided by the provision of stationary plates 92 which

are separated only a sufficient distance to provide a passageway for the arms alone until they arrive substantially at delivering position opposite to the end of the staple 5 raceway 94, and are there cut back, as indicated at 96, to permit the staples to pass. This arrangement serves not only to delay the passage of the staples to the outer ends of the arms, but also to remove from the 10 arms staples that are improperly positioned thereon, and permits the passage of only such staples as are in proper position to enter the raceway.

Upon the same side of the conveyer 46 as 15 the receptacle 72 is the receiving end of the button raceway, this raceway comprising two opposite side portions 98 and 100 which are provided respectively with a slot 102 for the button eyes and a groove 104 20 for the heads. The slot 102, as shown clearly in Fig. 5, is of sufficient width to permit buttons having heads of different diameters to pass through the raceway without any tendency for the eyes to bind upon the sides of 25 the slot, although preventing the eyes from turning over in the raceway. The raceway is slotted, as indicated at 106, opposite to the delivery point of the conveyer to receive the button eyes and it is suitably curved to 30 deflect the button immediately, as it is delivered from the wheel, into a horizontal position with its eye in the slot 102 and its head in the groove 104. Above the slot 106 and the receiving end of the raceway is a guide 35 108 which serves to direct the course of the button as it slides into the raceway and prevent it from falling over into the receptacle. This guide is pivotally suspended, so that if a button should fail to enter the 40 raceway properly or the raceway should become filled with buttons, the guide may yield to permit the button to be pushed over the raceway and into the receptacle by the following button. In order to dislodge from 45 the wheel any button that may be carried past the slot 106, the machine is provided with a bar 110 which extends obliquely over the sloping peripheral portion of the wheel and acts as a deflector to remove the 50 button from the wheel and return it to the receptacle 72.

In order to insure the advance of the buttons along the raceway and to remove from the raceway any foreign matter that may 55 become lodged therein, the machine is provided with means for directing blasts of air into the raceway, comprising a conduit 112 leading from an air pump 114 the piston of which is driven by a pitman 116 from a 60 crank on the pulley 20. The air pump is operated in timed relation to the button conveyer wheel and is arranged, as will be evident from an inspection of the drawings, to force a blast of air into the receiving end of 65 the raceway immediately after the admis-

sion of a button thereto. The air blast will thus assist and hasten the movement of the button along the raceway until it contacts with the end button of the series, and if there should be any tendency for any of the buttons of the series to stick in the raceway, the air blast will assist in closing the intervals between the buttons. 70

The delivery end portion of the button raceway, as shown in detail in Figs. 7 to 10 75 inclusive, directs the buttons downwardly and rearwardly to a position in which the button eye is over the anvil member 118 and in line with one leg of a staple which is held at the end of the staple raceway in position 80 to be advanced and driven by the staple driving member 120. The position of the end button is determined by a stop 122 which is arranged to contact with the button eye and comprises a shouldered portion of a 85 plate 124 which is disposed at one side of the path of movement of the driver 120 and assists in guiding the downward movement of the staples. The head of the end button in the raceway, as shown in Fig. 9, is positioned at the opposite side of the plate 124 from the driving member, and its eye projects on the other side of the plate in staple receiving position. 90

The fixed button supporting portions of 95 the button raceway terminate at some distance from the end of the raceway, and their places are supplied by springs 126 and 128 which are secured respectively to the side members 98 and 100 and are curved downwardly and rearwardly in position to support respectively the eyes and the heads of two or more of the end buttons. The end of the spring 126 rests normally in contact with the stop 122 so as to close the raceway, and the spring 128 is spaced a sufficient distance below the spring 126 to provide for the reception of button heads of different diameters, and therefore may or may not contact with the heads when the buttons are 100 at rest at the end of the raceway. As the button is engaged by the staple and depressed by the driving member for attachment to the work, the spring 128 at the side of the anvil 118 and the spring 126 over the 105 anvil are both depressed, and the latter spring is thereby separated from the stop 122 so as to permit the button to leave the raceway upon the subsequent feeding movement of the work. This depression of the 110 springs has also the important function of displacing or agitating the button or buttons directly at the rear of the end button, thereby obviating any tendency for the buttons to stick and fail to advance to the end of the 115 raceway; and when the end button is withdrawn and the springs snap back into position, the buttons supported by the springs are similarly affected, but in a more positive manner. By reason, moreover, of the curved 120

130

form of the springs, their sudden return to position has the effect of throwing the buttons toward the end of the raceway and of bringing the end button positively into contact with the stop 122.

The staple raceway 94, as shown in Fig. 8, is shaped to conform substantially to the contour of the illustrated novel staple hereinbefore referred to, which has upon its head 10 a substantially rectangular upstanding portion connected to the legs by portions of the head which are substantially straight and perpendicular to the legs and which form stock engaging shoulders, this construction 15 of the staple providing in the lower side of the head a substantially rectangular auxiliary recess which is elongated to permit a limited movement of adjustment of the button eye in the plane of the staple as shown 20 in Fig. 10. The staple raceway is thus provided with an upstanding portion 95 substantially rectangular in cross section, and has at each side of the portion 95 a plane face 97 to underlie and preferably be engaged by the shouldered portions of the 25 staples. This raceway includes also a cover or retainer 130 above the staples, and is curved to bring its end in close relation to the plate 124 so that the end staple will contact with and be stopped by the plate without falling through the space between the plate and the end of the raceway. In this 30 position the staple is in the path of the driver 120 with one of its legs in line with the eye of the button which is in contact with the stop 122. In order to permit the driver to 35 pass between the plate 124 and the end of the raceway, the end portion of the latter, including the cover 130, is pivotally connected 40 with the main portion, as indicated at 132, and is held by a spring 134 in its normal staple retaining position. As the driver descends the end portion of the raceway therefore will yield to permit the advance of the 45 staple and the driver as indicated in Fig. 9.

Below the end of the staple raceway is a guide member 136, the upper edge of which is curved or beveled at points below the legs of the staple, as indicated by dotted 50 lines in Fig. 9. This member serves, in cooperation with the plate 124, to guide the staple as it passes below the end of the raceway, and retain it in position to enter the button eye and the work in proper relation 55 to the clenching face of the anvil. One leg of the staple is further guided by means of a plate 138 which fits about the member 136 and projects at one side substantially across the space between this member and the plate 60 124. The plate 138 is made of spring metal, and its edge adjacent to the plate 124 is suitably beveled or curved to permit the driving member 120, upon its lateral feeding movement which will be subsequently 65 described, to move the plate in a direction

away from the guide member 124 and pass out from between this member and the guide plate 138.

It will be noted, particularly by reference to Figs. 7 to 10 inclusive, that the construction hereinbefore described comprises means for presenting a button with its eye substantially parallel to the work and means for positioning a staple with one of its legs in alignment with the opening of the button 70 eye relatively close to that side of the eye which is outside of the staple, and that the driving member 120 is constructed and arranged to enter the button eye with its outer edge at one side close to that portion of the 75 eye which is outside of the staple. With this arrangement that portion of the button eye which is within the staple is opposite the central portion of the staple head and there is no danger that the button eye 80 may be interposed between the stock and that portion of the head of the staple which is adjacent to the leg so as to prevent the staple from being fully driven. In the novel staple shown that portion 90 of the button eye which is within the staple is received within the recess in the staple head and the shouldered portions of the staple which connect the recessed portion with the legs are of such length that 95 one of them may pass with the adjacent leg through the button eye and both may be seated flat upon the stock by the operation of the driving member. The end of this member, as clearly shown in Figs. 7 and 10, 100 is provided with a substantially rectangular recess complementary to the form of the upstanding portion of the staple head, with projections 121 at the sides of the recess, each of which has a substantially straight 105 end face for engaging and pressing the respective shouldered portion of the staple flat upon the stock, and a substantially straight inner edge arranged to be located adjacent or contiguous to the respective side 110 face or edge of the upstanding portion of the staple head in the staple driving and work feeding operations. Between the two projections 121 the driving member presents also a substantially straight face which is 115 formed to stand in close relation to the horizontal bar across the upstanding portion of the staple head. The width of the forward projection 121, which is arranged to follow the shouldered portion of the staple through 120 the button eye, is substantially equal to the distance between the upstanding portion of the head and the outer edge of the staple, as clearly shown in Fig. 10.

The driving member as thus constructed 125 assists materially in keeping the staple straight as the latter is advanced and driven and in preventing distortion of the shape of the staple, particularly of the head portion of the staple, in the driving operation; 130

and by reason of the effective hold upon the staple which the driving member thus secures, as well as the engagement of one of the projections 121 in the button eye, the 5 driver is rendered particularly effective to feed the work when feeding movement is imparted thereto in the manner to be subsequently described.

The staple driving member 120 is carried 10 by a lever 140 which is pivoted at 142 upon a slide comprising two portions 144 and 146 rigidly connected and movable endwise in a guideway in the base 6, and a bracket or frame 148 secured to the member 146 and 15 serving as a direct support for the lever 140. The forward portion 144 of the slide carries the anvil 118 which is thus positioned always in the proper coöperative relation to the driving member 120. The lever 140 20 is oscillated from the shaft 4 by a cam 150 which is shaped for constant engagement with the opposite sides of a yoke shaped portion 152 at the rear end of the lever. The cam thus restrains the lever substantially 25 from oscillatory movement independent of the movement of the cam, but permits the lever to move endwise with the sides of the yoke 152 in sliding engagement with the cam. The slide member upon which the 30 lever and the anvil are supported is reciprocated, so as to impart feeding and return movements to the driver and the anvil, from a cam 154 on the shaft 4 of substantially the same shape as the cam 150 and 35 positioned diametrically opposite thereto. The cam 154 serves primarily to oscillate a frame 156 which is pivoted to the machine frame at 158 and has an opening providing opposite and substantially vertical 40 slideways which are engaged constantly by the cam 154 in the same relation as the cam 150 to the sides of the yoke 152. The frame 156 in its forwardly extending portion is provided with a substantially vertical 45 slideway 159 in which is mounted for sliding movement a block 160 having a bore in which is pivotally mounted a stud 162 on a plate 164 forming a portion of a slide of which the coöperating member 166 is received in a vertical slot 168 formed in a rearwardly projecting portion of the member 148. With this arrangement, as will be evident, oscillatory movement of the frame 156 will impart reciprocatory movement to 50 the slide which carries the lever 140 and the anvil, so as to feed the work after a button has been attached and then return the members into position for another button setting operation.

60 Adjustment of the extent of the feed movement in order to space the buttons as desired upon the work is effected through vertical adjustment of the slide 166 and its attached plate 164, which serves to position 55 the block 160 in the slideway 159 at differ-

ent distances from the pivotal point 158 of the frame 156. Convenient means for making this adjustment comprises a rack 170 secured to the bracket 148 adjacent to the slot 168, and a coöperating pinion 172 mounted upon the end of a spindle 174 which is journaled in a bushing 176 projecting from the slide member 166 through the plate 164. The outer surface of this bushing is screw threaded to receive a collar 178 which may be turned thereon to press the parts 164 and 166 into firm engagement with the sides of the bracket 148 and thus secure the block 160 in any position of adjustment. The spindle 174 may be turned 75 by means of a hand wheel 180 loosely mounted thereon and provided with a pin 182 for engagement in recesses 184 in a head 186 secured upon the end of the spindle. A spring 188 between the end of the collar 178 and the hand wheel tends to position the latter normally as shown in Fig. 6 with the pin 182 in one of the recesses 184. In this position the wheel may be turned to rotate the spindle and the pinion 90 172 and thereby change the length of the feed movements of the anvil and the staple driver. Previous to such adjustment, however, it is necessary to loosen the collar 178, and this, as well as the tightening of the 95 collar, is effected by means of the hand wheel through the engagement of a pin 190 on the wheel in one of a series of recesses 192 in the end of the collar 178 when the wheel is pressed endwise on the spindle in 100 opposition to the force of the spring 188. The plate 164, as shown in Figs. 2 and 6, carries a pointer which serves in coöperation with a scale on the bracket member 148 to indicate the proper adjustment for securing the desired spacing between adjacent buttons or fasteners.

By reference to Fig. 2 it will be seen that when the slide 148 is at its forward limit of movement, with the anvil and the staple 110 driver in proper coöperative relation to the raceways for attaching a button to the work, the slideway 159 is parallel to the slot 168, and that adjustment of the plate 164 and the block 160 to vary the extent of the feed 115 movement will therefore have no effect upon the relation of the slide 148 and the frame 156 when the parts are in this position. Whatever may be the extent of the feed movement, therefore, the forward limit of 120 movement of the slide 148 will be the same, as is necessary for the proper coöperative relation of the anvil and the driver with the raceways.

The feeding movement of the anvil and 125 the staple driver, as previously stated, takes place while the driver is at the end of its driving movement, the yoke shaped portion 152 of the lever 140 at this time sliding rearwardly over the cam 150. In order to pre- 130

vent excessive friction between the cam and the lever and facilitate the feed movement, the anvil 118 is mounted upon the slide member 144 with provision for a slight 5 downward or yielding movement away from the driver 120 at the beginning of the rearward movement of the slide. To this end the anvil has a shank portion 194 extending through a bore in the slide in position to 10 be acted upon by a cam 196 set in the bottom of the slideway. The anvil is prevented from turning by means of a pin 198 which engages in a slot in the shank portion 194, as well as by a pin 200 which engages in a 15 recess in the member 144. The cam 196, as thus arranged, serves to upraise the anvil when the slide is in its foremost position, and when the slide is moved to the rear permits the anvil to yield sufficiently to relieve 20 the driver carrying lever 140 from excessive pressure upon its operating cam.

Between the feeding movements of the driver and the anvil and while these members are returning to their starting positions, the work must be held effectively in the position to which it has been advanced. For this purpose the machine is provided 25 with coöperating clamp members 202 and 204 positioned respectively in front of the driving member and of the anvil. The upper member 202 serves as a stationary work abutment and is adjustable to determine the position of the plane in which the work is held, while the member 204 is carried by a lever 206 pivoted to the base at 208 and held by a spring 210 in position to press the work against the member 202, the extent of such movement of the lever being limited by an adjustable stop 212. 30 The lever is connected by a chain 214 to a foot treadle, not shown, whereby the presser 204 may be swung downwardly away from the end of the anvil 118 to the extent permitted by a screw 216 engaging in a slot 35 218 in the lever. Such movement of the presser member permits the work to be inserted in the machine and adjusted upon the anvil in position to receive the first fastener, and is of particular advantage in re- 40 pair work where, for example, it is necessary to set a single fastener at the lower end of a button fly on a shoe and it is difficult to adjust the material in the required position upon the clenching face of the 45 anvil. In order to facilitate this operation also the anvil 118 is made as narrow as possible while still providing sufficient area of clenching surface for setting the staple.

In the operation of the machine the pul- 50 ley 2 is continuously driven so as to operate through the described connections the button and staple conveyers which deliver, in the manner previously explained, the buttons and the staples to their respective raceways 55 whereby they are presented in the proper

relative positions for attachment to the work through the movements of the driving member. If necessary, when starting the machine, the shaft 4 may be rotated manually to supply the raceway with staples and buttons. After the proper adjustment has been made for the required spacing of the buttons, the treadle connected with the lever 206 is operated and the presser member 204 there- 60 by depressed to permit the work to be prop- 70 erly positioned upon the anvil 118 for the attachment of the first button of the series. Such adjustment is facilitated by reason of the fact that the clutch is released to stop the machine automatically with the parts 80 positioned as represented in Figs. 1 and 2 and the driving member and the anvil in separated relation. When the work has been adjusted, the presser member is released and through the operation of the spring 210 85 presses the work constantly against the abutment 202 during subsequent operations.

The clutch actuating treadle is next de- 90 pressed to connect the shaft 4 to the pulley 2. This results immediately in movement 95 of the lever 140 through the operation of the cam 150 to advance the driving member 120 toward the anvil, the cam 154 in the meantime and during the entire downward move- 100 ment of the driving member presenting its concentric portions in engagement with the opposite vertical sides of the opening in the frame 156 so as to prevent any movement of the anvil and lever supporting slide. The end of the driving member 120 in its advance 105 engages the top of the staple which is held at the end of the raceway 94 in contact with the guide plate 124, and pressing back the yielding end portion of the raceway, as shown in Fig. 9, advances the staple down- 110 wardly between the plate 124 and the guide members 136 and 138, passing one leg of the staple through the eye of the button at the end of the button raceway, as shown in Fig. 8, and finally in coöperation with the anvil 118, sets the staple in the work in the manner shown in Fig. 10 with one of the forward projections 121 at the end of the driving member engaged in the eye of the button. During this movement of the driving 115 member the spring 126 is depressed, as shown, to provide an outlet for the button eye between the spring and the stop 122, and the spring 128 under the head of the button is also depressed, the depression of 120 these springs, as previously explained, serv- 125 ing also to agitate other buttons at the rear of the end button so as to obviate any tendency for the buttons to stick in the curved portion of the raceway.

The driving member having arrived at the end of its staple setting movement, the concentric portions of the cam 150 come into engagement with the opposite sides of the yoke portion 152 of the lever 140 so as to 130

retain the driving member in the relation to the work assumed at the end of the setting movement, and the cam 154 simultaneously starts to swing the frame 156 rearwardly and thereby to draw the slide which supports the anvil and the lever 140 toward the rear of the machine and advance the work between the rest 202 and the yielding presser member 204 into position to receive the next button attaching operation. At the beginning of this feed movement the button is withdrawn from the raceway and the springs 126 and 128 snap into position, thereby further agitating the buttons in the raceway and imparting to them an impulse toward the end of the raceway so as to insure that the eye of the end button shall be positioned in engagement with the stop 122. At the beginning of the feed movement also the shank portion 194 of the anvil slips off of the cam 196 and thus permits the anvil to yield slightly and relieve somewhat the pressure of the lever 140 upon the cam 150. During the entire feed movement the latter cam retains the lever in position to hold the driving member in effective feeding relation to the work.

At the end of the feed movement above described the cam 154 holds the slide in retracted position while the cam 150 swings the lever 140 in the opposite direction to separate the driving member from the work, after which the latter cam restrains the lever from swinging movement while the cam 154 returns the driving member and the anvil to starting position. During this movement the anvil slips under the work which is held by the clamp members in the position to which it has been advanced, and at the end of the movement the anvil 118 is projected upwardly by the cam 196.

If the operator keeps his foot upon the clutch actuating treadle, the above described operations will be repeated indefinitely, but if it is desired to attach only a single button the treadle will be released in time to disconnect the clutch when the parts arrive at the positions represented in Figs. 1 and 2. It will be understood that the speed practicable for the operation of the machine permits the clutch treadle to be released in time to stop the button attaching operations at any point desired.

The novel button and staple feeding mechanism herein disclosed is not claimed in this application but in another application, Serial No. 12,143, filed March 4, 1915.

Although the invention is disclosed as embodied in a machine having the precise details of construction shown and described, it should be understood that the invention is not thus limited in its application but is susceptible of other embodiments within the spirit and scope of the appended claims. It should also be understood that the terms

"fastener" and "button" in the claims are to be construed broadly for the purpose of giving effect to my intention to claim all the protection whereto I am entitled for the various novel features of the invention.

Having described the invention, what I claim as new and desire to secure by Letters Patent of the United States is the following:

1. A machine of the class described having, in combination, an anvil, a raceway for a series of buttons arranged to present the end button of the series with its eye adjacent to work on the anvil, a raceway for fasteners arranged with reference to the button raceway to present a fastener in alignment with the eye of the end button of the series and on the same side of the work, and means for driving the fastener through said button eye and against the anvil. 75

2. A machine of the class described having, in combination, an anvil, a raceway for a series of buttons arranged to present the end button of the series in attaching position with its eye over the work on the anvil, a staple raceway terminating in position to present a staple with one leg in alignment with the eye of the end button of the series, and means for driving the staple through said button eye and against the anvil. 80

3. A machine of the class described having, in combination, staple driving means, an anvil, and a stationary button raceway arranged to present a button adjacent to work upon the anvil with its eye in position 90 to be entered by one leg of the staple driven by said means. 95

4. A machine of the class described having, in combination, a staple driver, a staple raceway arranged to direct a staple 105 into the path of movement of said driver, an anvil in line with the direction of movement of the driver, and means for presenting a button adjacent to the work upon the anvil with the opening in its eye in line with one 110 leg of the staple advanced by the driver and for supporting it substantially in this position during the driving and clenching of the staple. 100

5. A machine of the class described having, in combination, an anvil, a driving member, a fastener raceway and a button raceway relatively arranged to present a button and a fastener in position to permit the fastener to be inserted through the eye of the 115 button and driven against the anvil by the movement of the driving member, and means for operating the driving member to drive the fastener through the eye of the button while the button is so presented. 120

6. A machine of the class described having, in combination, an anvil member, a fastener inserting member, a button raceway arranged to present buttons in attaching position with the eye of the end button adjacent 125 130

to work on the anvil member, means for positioning a fastener to permit the fastener to be driven through the eye of the button and then through work upon the anvil member, and means for then imparting continuous movement to the fastener inserting member to drive the fastener through the button eye and against the anvil member.

7. A machine of the class described having, in combination, means for presenting a button with its eye adjacent to the work and substantially parallel to the plane of the work, means for presenting a staple with a leg in line with the opening in the button eye, and means for driving the staple comprising a driving member having a portion formed to enter the eye of the button and press a portion of the head of the staple flat upon the work.

20 8. A machine for attaching buttons by means of staples having, in combination, means for presenting a button with its eye adjacent to the work and substantially parallel to the plane of the work, and means for driving a staple having a work engaging shoulder of less size than the size of the eye of the associated button into the work with one leg of the staple outside of the button eye and the other leg within the eye and relatively close to one side of said eye to permit full engagement of the shoulder of the staple with the work without binding the button eye.

9. A machine for attaching buttons by means of staples having, in combination, means for presenting a button with its eye adjacent to the work, means for presenting a staple with a leg thereof aligned with a portion of the opening in the button eye relatively close to one side of the eye, and means for driving the staple comprising a driving member constructed and arranged to enter the button eye relatively close to that side of the eye adjacent to which said leg is driven.

10. A machine for attaching buttons by means of staples comprising, in combination, a staple driving member having a projection formed to engage the head of the staple at one side thereof and to enter the eye of the button, the width of said projection being less than the width of the opening in the button eye, and means for presenting a button with its eye in position to be entered by said projection of the driving member relatively close to one side of the eye.

11. In a machine for attaching buttons by means of staples each of which has in its head a recess and a work engaging portion at one side of the recess of a length to permit said portion and the adjacent leg of the staple to be inserted through the button eye in the button attaching operation, a driving member for the staple having a projection formed to engage said work engaging por-

tion of the staple and to enter the button eye, the combined width of said projection and the material of the staple being no greater than the width of the opening in the button eye.

12. In a machine for attaching buttons by means of staples each of which is formed upon the head with an upstanding portion sufficiently close to a leg of the staple to permit the leg to be driven its full length into the work when the eye of the button is substantially parallel to the plane of the work, a driving member for the staples having a projection formed to engage the head of a staple at the side of said upstanding portion and of a width corresponding substantially to the distance between said upstanding portion and the outer edge of the staple.

13. In a machine of the class described comprising means for inserting staples having upon their heads upstanding portions the sides of which are substantially parallel to the legs of the staples, a driving member for the staples having a projection formed with a substantially straight side for engagement with one of the sides of said upstanding portion on a staple, and means for imparting movement to said member subsequent to its driving movement to feed the work by engagement of said projection with the upstanding portion of the staple.

14. In a machine of the class described, comprising an anvil, means for supplying a succession of staples in position to be driven, and a driving member for the staples having a recess, the base of which is formed as a substantially straight, elongated portion, said driver at one side of said recess terminating in end portions which are substantially straight and parallel to the work supporting surface of the anvil, the sides of said recess being arranged in substantial regularity with said end portions whereby said driver is adapted to engage closely corresponding surfaces of a staple having a head portion substantially complementary to the driver to adapt the driver not only to support the entire length of the button retaining bar thereof, but also to bring the work engaging portions of the staple into flat engagement with the work so that the wedging of a button eye between the stock and the work engaging portions thereof is avoided.

15. In a machine of the class described comprising means for inserting staples each of which is formed upon its head with an upstanding portion including a substantially horizontal bar, a driving member for the staples formed to engage the head of a staple at the sides of the upstanding portion thereon and formed to present a substantially straight surface over said bar to prevent distortion of the staple during the driving operation.

120
125
130

16. In a machine for inserting staples, means for supplying staples successively in position to be driven, and a driving member for the staples provided with a recess whose 5 base is formed as a substantially straight, elongated portion arranged to engage a correspondingly shaped portion of a staple at all portions throughout its length, and end portions constructed and arranged to engage 10 stock engaging portions of the staple which extend outwardly from the head portion thereof and join the head to the legs to cause said stock engaging portions to lie flat upon the work.
15. 17. In a machine for attaching buttons by means of fasteners, a driving member for the fasteners having a projection formed to engage in the eye of a button, and means for moving said member to feed the work while 20 said projection is thus engaged.
18. In a machine for attaching shoe buttons or the like, a raceway for the buttons, a button fastener driving member formed to engage in the eye of a button in the race- 25 way, and means for moving said driving member to withdraw the button from the raceway.
19. In a machine for inserting staples in the eyes of buttons, a button raceway, a staple 30 driving member having a projection formed to engage in the eye of a button in the raceway, and means for moving said member to withdraw the button from the raceway while said projection is thus engaged.
35. 20. In a machine for attaching buttons by means of staples having upstanding portions on their heads, a staple driving member having a recess to receive the upstanding portion of the staple, and means for moving 40 said member to feed the work while the upstanding portion of the staple is within said recess.
21. A machine of the class described, having, in combination, an anvil for supporting 45 a piece of material, a member for inserting fasteners in said material, and means for imparting substantially rectilinear movement to the anvil rearwardly from the front of the machine to feed the material after a fastener has been inserted.
50. 22. A machine of the class described having, in combination, an anvil for supporting a piece of material, a member for inserting fasteners in said material, operating means 55 for said member extending forwardly from the rear of the machine, and means for imparting substantially rectilinear rearward movement to said member to feed the material while said member is substantially at the 60 end of its inserting movement.
23. A machine of the class described having, in combination, an anvil for supporting a piece of material, a member for inserting fasteners in said material, and means for 65 imparting substantially rectilinear movement to the anvil and said member rearwardly from the front of the machine to feed the material after a fastener has been inserted. 65
24. A machine of the class described hav- 70 ing, in combination, a pivoted lever, a fastener driving member carried by the lever, means for swinging the lever to impart driving movement to said member, and means for imparting a substantially right line feed- 75 ing movement to the lever.
25. A machine of the class described hav- 80 ing, in combination, a pivoted lever, a fastener driving member carried by the lever, means for swinging the lever to impart driving movement to said member, and means for moving the lever bodily in substantially a straight line to feed the work while said member is substantially at the end of its driving movement. 85
26. A machine of the class described hav- 90 ing, in combination, a fastener raceway, a pivoted lever, a fastener inserting member carried by the lever at one end thereof, arranged to remove fasteners from the race- 95 way and insert them in the work, the other end of said lever being formed with a yoke-shaped portion, and a cam arranged within said portion of the lever for imparting fastener inserting and reverse movements to the lever. 95
27. In a machine for attaching buttons, a slide, a lever fulcrumed upon the slide, a driving member carried by the lever, means for supplying staples to said driving member, means for swinging the lever to impart driving movement to said member, and means for moving the slide to impart feeding movement to work in which a staple has been inserted by the driving member in the line of the head of the staple. 100
28. A machine of the class described hav- 105 ing, in combination, a slide, a lever fulcrumed upon the slide, a fastener driving member carried by the lever, means for swinging the lever to impart driving movement to said member, and means for moving the slide to carry the lever substantially in the direction of its length while said member is substantially at the end of its driving movement. 110
29. A machine of the class described hav- 115 ing, in combination, a slide, a lever fulcrumed upon the slide, a fastener driving member carried by the lever, means for supplying fasteners to said driving member, cam means for oscillating the lever to cause the driving member to engage and insert a fastener, and cam means for reciprocating the slide to impart feeding movement to the work by engagement of the driving member with the head of the inserted fastener. 120
30. A machine of the class described hav-

- ing, in combination, a pivoted lever, a fastener driving member carried by the lever, cam means for swinging the lever to impart driving movement to said member, and 5 means for imparting an additional feeding movement to the lever, said cam means being constructed to restrain the lever substantially from swinging movement during the feeding movement thereof.
- 10 31. A button attaching machine having, in combination, a slide, a lever fulcrumed upon the slide, a fastener driving member operated by the lever, means for supplying staples to be driven by said member, means for reciprocating the slide to impart feeding movement to the lever and its driving member, and a cam for swinging the lever, said cam being constructed to restrain the lever substantially from swinging movement during 20 the movement of the slide in order to hold the driving member in engagement with the head of the inserted staple to cause the feeding movement of the driving member to be imparted to the work.
- 15 32. A fastener inserting machine having, in combination, a base, a slide mounted thereon, a lever fulcrumed upon the slide, a fastener driving member operated by the lever, means for supplying fasteners to an inserting point fixed with relation to the base, means for swinging the lever to drive the fasteners, and a cam for reciprocating the slide, said cam being constructed to restrain the slide substantially from movement during 30 the swinging movement of the lever to hold the driving member in alignment with the fastener.
- 25 33. A button attaching machine having, in combination, a slide, a lever fulcrumed upon the slide, a fastener driving member formed to engage one side of the upstanding portion of a button attaching staple and operated by the lever, means for supplying staples to said driving member, means for swinging 40 the lever, means for moving the slide to impart feeding movement to the lever, and means for locking the lever from swinging movement during said movement of the slide to hold the driving member in engagement 45 with one side of the upstanding portion of an inserted staple so that the feeding movement of the lever will be imparted to the work.
- 50 34. A button attaching machine having, in combination, a base, a slide member mounted thereon, means for supplying staples having a vertical shoulder to a predetermined position with respect to said base, a lever member fulcrumed upon the slide member, a driver for fasteners operated by the latter member and formed to engage the head and vertical shoulder of said staples, and coöperating means arranged for swinging the lever to drive the staples and for reciprocating the 55 slide to feed the work, said means being constructed to prevent substantially said movement of either member during said movement of the other member whereby the driver will be brought into registering engagement with the shouldered head of the 60 staples during driving and held against said vertical shoulder to impart the work feeding movement of the slide to the work.
- 65 35. A button attaching machine having, in combination, a raceway for supplying staples formed with a substantially rectangular upstanding head portion, a slide, a lever fulcrumed upon the slide, a fastener driving member operated by the lever, and formed with a recess complemental to said upstanding head portion, a cam shaft, and a pair of cams on the shaft arranged respectively for swinging the lever to drive the staples without distorting the head portion, and for moving the slide to feed the work by engagement 70 of the driving member with the vertical side of said upstanding head portion.
- 75 36. A machine of the class described having, in combination, a slide, a driver for fasteners fulcrumed on the slide, means for oscillating said driver, a pivoted member, a connection between said member and the slide, means for swinging said member to impart work feeding movement to the slide, and manually operable means carried by said 80 connection and engaging the slide arranged to be rotated to adjust the effective length of the pivoted member.
- 85 37. A machine of the class described having, in combination, a slide, fastener setting means carried by the slide, an oscillatory member, a connection between said member and the slide, means for swinging said member to impart work feeding movement to the slide, and rotatable means interposed between the connection and the slide arranged to adjust said connection with respect to the center of oscillation of said member to thereby vary the extent of movement imparted to the slide from said member.
- 90 38. A machine of the class described having, in combination, a slide, fastener setting means carried by the slide, an oscillatory member for operating the slide, means connecting said member with the slide, said member being constructed to receive said connecting means at different distances from its axis to vary the extent of movement imparted to the slide and rotatable means arranged to move the connecting means and hold it in adjusted position.
- 95 39. A machine of the class described having, in combination, a slide, fastener setting means carried by the slide, a pivoted frame for operating the slide, said frame having a 100 guideway, a block slidable to different positions on said guideway, and means for adjustably connecting said block to the slide.
- 105 110 115 120 125

for imparting movement from the frame to the slide, said means comprising a manually operated clamping device for holding the connecting means in adjusted position with respect to the slide.

40. A machine of the class described having, in combination, a slide provided with means for operating upon fasteners and having a portion forming a guideway extending transversely to the direction of movement of the slide, a pivoted operating member, and a member slidable upon the guideway and arranged to connect with said operating member at different distances from its pivotal point upon movement of said slidable member along the guideway and means movable to two positions arranged in one position to accurately adjust the slidable member along the guideway in the slide and in its other position to clamp the slidable member to the slide in its adjusted position.

41. A machine of the class described having, in combination, fastener setting means, mechanism for moving said means to feed the work, and means operative through the feeding movement of said fastener setting means to cause said means to lessen its pressure upon the work during the feeding movement.

30 42. A machine of the class described having, in combination, a fastener driving member, means for imparting movement to said member to feed the work while it is positioned substantially at the end of its driving movement, and means operative through the feeding movement of said member for lessening the pressure of said member upon the work during the feeding movement.

43. A machine of the class described having, in combination, a fastener driving member, means for imparting additional movement to said member to feed the work after its driving movement, a cam for imparting driving movement to said member, connecting means between the cam and said member arranged for sliding movement over the cam incidental to the feeding movement of the member, and means for lessening the pressure of said connecting means upon the cam during the feeding movement of the member.

44. A machine of the class described having, in combination, an anvil member and a fastener driving member coöperating to secure the fasteners in the work, means for imparting movement to said members to feed the work while the work is gripped between the members, and a stationary cam arranged to control the position of one of said members to cause said member to lessen its pressure upon the work during the feeding movement.

45. In a machine of the class described, the combination with a fastener driving

member, of an anvil, means for moving the anvil to feed the work after a fastener has been inserted in the work, and means constructed and arranged to permit movement of the anvil away from the driving member in a direction transverse to the plane of the work at the beginning of its feeding movement.

46. In a machine of the class described, the combination with a fastener driving member, of a movable slide and an anvil carried by the slide and movable therewith to feed the work, and means for controlling the position of said anvil constructed and arranged to permit it to move in a direction transverse to the direction of movement of the slide to lessen the pressure on the work during the feeding movement.

47. In a machine of the class described, the combination with a fastener driving member, of a movable slide and an anvil carried by the slide and movable therewith to feed the work, said anvil being mounted upon the slide with provision for additional movement in a direction transverse to the direction of feeding movement of the slide to lessen the pressure on the work during the feeding movement, and means for returning the anvil to its first position relatively to the slide during the return movement of the slide.

48. In a machine of the class described, the combination with a fastener driving member, of a slide movable to feed the work subsequent to the driving movement of said member, an anvil member carried by the slide and movable relatively thereto to lessen its pressure on the work during the feeding movement, and a cam arranged to engage a portion of said anvil member to restore it to clenching position at substantially the end of movement of the slide in one direction.

49. In a machine of the class described, the combination with a fastener driving member, of a slide movable to feed the work subsequent to the driving movement of said member, an anvil carried by the slide and movable relatively thereto in directions transverse to the direction of movement of the slide, and means for imparting such movement to the anvil toward the path of movement of the driving member at substantially the end of the return movement of the slide, said means being constructed to permit movement of the anvil in the opposite direction with reference to the slide to lessen its pressure upon the work during the feeding movement of the slide.

50. A machine of the class described having, in combination, means for securing fasteners in the work comprising an anvil, said means being movable also to feed the work, and a plurality of coöperating work positioning means arranged to clamp the work

- with yielding pressure during the feeding movement thereof, one of said means being normally fixed but adjustable to vary the position of the plane in which the work is 5 held with respect to the plane of the anvil surface.
51. In a machine of the class described, the combination with an anvil and a driving member, of a stationary work positioning member arranged to engage the work upon the same side as the driving member, and a yielding presser member arranged for continuous engagement with the other side of the work.
52. In a machine of the class described, the combination with an anvil arranged to engage one side of the work, of a stationary work positioning member arranged to engage the work upon its opposite side, and 10 a presser member arranged to engage the work continuously upon the same side as the anvil to press the work against said positioning member, said presser member being movable to permit adjustment of the 15 work upon the anvil.
53. In a machine of the class described, the combination with a driving member arranged to advance the fasteners toward the work, of guiding means for the fasteners 20 including a member yieldable to permit movement of the driving member at an angle to the direction of its driving movement.
54. In a machine of the class described, the combination with a driving member arranged to advance the fasteners toward the work and movable laterally to feed the work, of guiding means for the fasteners including a member yieldable to permit said feeding movement of the driving member.
55. In a machine of the class described, the combination with a driving member arranged to advance the staples toward the work, of means for guiding one leg of the 45 staple during the advancing movement thereof, said means comprising a member having provision for yielding movement to permit lateral movement of the driving member in addition to its driving movement.
56. In a machine of the class described, the combination with a driver, of a pair of oppositely disposed members arranged to form a guideway through which the staples 55 are advanced by the driver, and a plate extending substantially across the space between said members at one side of the guideway, said plate being movable upon contact of the driver therewith to permit the driver 60 to pass laterally out of the guideway.
57. In a machine for attaching buttons by means of fasteners, the combination with an anvil and a driving member, of means forming a guideway for the fasteners driven to 65 ward the anvil by said member, said means being formed also to engage a button to position it with its eye in the path of movement of a fastener.
58. In a machine for attaching buttons by means of fasteners, the combination with an anvil and a driving member, of a plate for guiding the movement of the fasteners driven toward the anvil by said member, said plate having a shouldered portion for engaging a button eye to position it in the path of movement of the fasteners, and means for directing buttons into contact with said portion of the plate.
59. In a machine of the class described, the combination with a driving member, of 70 a button raceway arranged to present a button in position to receive a fastener advanced by said member, said raceway having a yielding portion movable under the impulse of the driving member to provide an 75 outlet for the button from the raceway, and means for moving the button out of the raceway while said yielding portion is depressed by the driving member.
60. In a machine of the class described, the combination with a driving member, of 80 a button raceway arranged to present a button in position to receive a fastener advanced by said member, said raceway having a yielding portion movable under the impulse of the driving member to provide an 85 outlet for the button from the raceway, and means for moving the button out of the raceway while said yielding portion is depressed by the driving member.
61. In a machine of the class described, the combination with a driving member and an anvil, of a button raceway arranged to present a button over the anvil in position for attachment to the work, said raceway 90 having a yielding portion movable under the impulse of the driving member to provide an outlet for the button from the raceway, and means for imparting movement to the driving member in addition to its driving movement to remove the button from the raceway.
62. In a machine of the class described, the combination with a driving member and an anvil, of a button raceway arranged to 95 present a button over the anvil in position for attachment to the work, said raceway having a yielding portion movable under the impulse of the driving member to provide an outlet for the button from the raceway, and means for feeding the work to remove the button from the raceway while 100 said yielding portion is depressed by the driving member.
63. In a machine of the class described, the combination with a member for driving 105 fasteners, of a raceway arranged to present a button with its eye in position to receive a fastener driven by said member, said race-

way having a button supporting portion yieldable to the driving movement of said member.

64. In a machine of the class described, 5 the combination with a member for driving fasteners and an anvil coöperating with said member, of a raceway arranged to present a button over the anvil with its eye in position to receive a fastener driven by said 10 member, the raceway having a button supporting portion movable toward the anvil under the impulse of the driving member.

65. In a machine of the class described, 15 the combination with a fastener driving member, of a raceway for buttons or the like having yielding means for supporting a plurality of the buttons at the end of the raceway, said means being yieldable under the impulse of the driving member to dis- 20 place the buttons supported thereby and prevent them from sticking in the raceway.

66. A machine of the class described having, in combination, a raceway for buttons or the like, and a fastener driving member 25 arranged to engage the end button in the raceway and withdraw it from the raceway, said raceway having means for supporting a plurality of the buttons near the end of the raceway arranged for yielding move- 30 ment under the impulse of the driving member and for return movement upon the withdrawal of the end button so as to agitate the buttons and prevent them from sticking in the raceway.

67. In a machine for attaching buttons or the like, the combination with a fastener inserting member, of a raceway for the buttons having a portion yieldable under the impulse of said inserting member to open 40 a passageway for the buttons from the race- way.

68. In a machine of the class described, the combination with a driving member and an anvil, of a button raceway arranged 45 to present a button over the anvil, said raceway having a yielding support for the button eye movable toward the anvil under the impulse of the driving member, and a yieldable support for the button head movable at 50 one side of the anvil.

69. In a machine of the class described, the combination with a driver movable in a predetermined path, of a raceway having a separate end portion movable relatively to 55 the remaining portion thereof, and means for positioning the end of the raceway normally in the path of movement of the driver.

70. In a machine of the class described, 60 the combination with a driver movable in a predetermined path, of a guide member at one side of the path of movement of the driver, and a raceway having an end portion directed toward said guide member 65 from the opposite side of the path of move-

ment of the driver and pivotally connected with the remaining portion of the raceway.

71. In a machine of the class described, the combination with a driver movable in a predetermined path, of a raceway having a 70 curved end portion directed toward said driver and pivotally connected with the remaining portion of the raceway, and spring means for projecting said end portion of the raceway normally in the path of move- 75 ment of the driver.

72. In a machine of the class described, the combination with a driver movable in a predetermined path, of a guide member at 80 one side of the path of movement of the driver, and a raceway having a separate end portion directed toward said guide member and movable relatively to the remaining portion of the raceway.

73. In a machine of the class described 85 comprising means for setting staples each of which has upon its head an upstanding portion formed with substantially straight sides, staple setting instrumentalities comprising means having substantially straight 90 portions arranged to be positioned in substantially parallel close relation to the sides of the upstanding portion of a staple to prevent distortion of the head of the staple during the setting operation. 95

74. In a machine of the class described comprising means for setting staples each of which has upon its head a substantially rectangular upstanding portion, staple setting instrumentalities comprising means 100 having substantially straight portions arranged to be positioned in substantially parallel close relation to the sides and top of the upstanding portion of a staple to prevent distortion of the head of the staple during the setting operation. 105

75. In a machine of the class described comprising means for setting staples each of which has upon its head an upstanding portion connected to the legs by substantially 110 straight portions of the staple head, staple setting instrumentalities comprising a member having substantially straight faces for engagement with said straight portions of a staple head and means for closely embrac- 115 ing the upstanding portion of the staple to prevent distortion of said portion during the setting operation.

76. In a machine of the class described comprising means for setting staples each of 120 which has upon its head an upstanding portion, staple setting instrumentalities comprising relatively movable driving and anvil members, one of said members having a recess substantially complementary to the 125 shape of said upstanding portion of the staple head to permit said member to engage and prevent distortion of the upstanding portion of the staple head in the staple setting operation. 130

77. In a machine of the class described comprising means for setting staples each of which has upon its head a substantially rectangular upstanding portion, staple setting instrumentalities comprising relatively movable driving and anvil members, one of said members being formed to engage the staple head at each side of the upstanding portion and to embrace said upstanding portion in close relation thereto to prevent distortion of said portion of the staple during the setting operation.

78. A machine for attaching buttons by means of staples having, in combination, means for presenting a button with its eye substantially parallel to the work, and means for driving a staple with one of its legs outside of the button eye and the other leg inside of the eye relatively close to that side of the eye which is outside of the staple.

79. A machine for attaching buttons by means of staples having, in combination, means for presenting a button with its eye substantially parallel to the work, and staple setting instrumentalities comprising driving and anvil members relatively movable to cause one of the legs of the staple to enter the work outside of the button eye and the other leg to enter the eye relatively close to that side of the eye which is outside of the staple.

80. In a machine for attaching buttons by means of staples each of which is formed with an auxiliary recess in the inner side of its head, staple setting instrumentalities comprising driving and anvil members relatively movable to cause the legs of a staple to enter the work and to be clenched upon the anvil, and means for presenting a button with its eye substantially parallel to the work in position to be entered by one of the legs of the staple and with that portion of its eye which is in line with the staple head opposite to said auxiliary recess in the head.

81. In a machine for attaching buttons by means of staples each of which is formed with a recess in the inner side of its head, an anvil member, a staple driving member movable to drive a staple through the work and against the anvil member, and means for presenting a button with its eye adjacent to the

work in position to be entered by one of the legs of the staple and with that portion of its eye which is in line with the staple head in position to be received within said recessed portion of the staple head when the staple is driven.

82. In a machine for attaching buttons by means of staples, relatively movable driving and anvil members constructed and arranged to drive a staple into the work with one of the legs of the staple inside of a button eye and the other leg outside of the eye, one of said members being formed and arranged to enter the button eye and to press a portion of the head of the staple into close engagement with the work.

83. In a machine for attaching buttons by means of staples, a staple driving member having a projection formed and arranged for engagement within the eye of a button in the staple driving operation, said projection being of sufficient width to force a portion of the head of the staple into close engagement with the work.

84. In a machine for attaching buttons by means of staples, a staple driving member having a projection formed and arranged for engagement within the eye of a button in the staple driving operation, said member being constructed to position the staple with one of its legs in line with said projection, and the projection being formed to force a portion of the head of the staple adjacent to said leg into close engagement with the work.

85. In a machine of the class described, a staple driving member having projections formed to engage the head of a staple substantially in line with the staple legs, said projections being of sufficient width to force portions of the head of the staple adjacent to the legs into close engagement with the work while one of the projections is arranged to enter the eye of a button presented for attachment to the work.

In testimony whereof I have signed my name to this specification in the presence of two subscribing witnesses.

FRANK LESLIE HARMON.
